US0D1044228S

(12) United States Design Patent (10) Patent No.: US D1,044,228 S
(45) Date of Patent:  Oct. 1, 2024

(54) SHOE

(71) Applicant: ROTHY'S, INC., San Francisco, CA (US)

(72) Inventor: La Vion Gibson, San Francisco, CA (US)

(73) Assignee: ROTHY'S, INC., San Francisco, CA (US)

() Term: 15 Years

(21) Appl. No.: 29/868,258

(22) Filed: Nov. 28, 2022

(51) LOC (14) Cl. 02-04

(52) U.S. Cl.

USPC D2/923; D2/907

(58) Field of Classification Search

USPC D2/902-912, 920, 923-945, 954, 959, D2/960, 978; 2/902-912, 920, 923-945, 2/954, 959, 960, 978

CPC A43B 1/009; A43B 1/10; A43B 1/108; A43B 1/14; A43B 5/00; A43B 5/06; A43B 5/10; A43B 13/00; A43B 13/02; A43B 13/04; A43B 13/06

(57) CLAIM

The ornamental design for a shoe, as shown and described.

DESCRIPTION

FIG. 1 is a front rear perspective view of a sneaker showing our new design;

FIG. 2 is a front view of the design shown in FIG. 1;

FIG. 3 is a rear view of the design shown in FIG. 1;

FIG. 4 is a right side view of the design shown in FIG. 1;

FIG. 5 is a left side view of the design shown in FIG. 1;

FIG. 6 is a top view of the design shown in FIG. 1; and,

FIG. 7 is a bottom view of the design shown in FIG. 1.

Color forms no part of the claimed design. Broken lines are included for the purpose of illustrating portion of the sneaker that form no part of the claimed design.

1 Claim, 5 Drawing Sheets
